UNITED STATES PATENT OFFICE.

RICHARD BERNHARD AND JACOB M. SHOLL, OF MILWAUKEE, WISCONSIN, ASSIGNEES
TO POWER AND MINING MACHINERY COMPANY, A CORPORATION OF NEW JERSEY.

LUBRICATING DEVICE FOR GYRATORY CRUSHERS.

1,145,967.

Specification of Letters Patent. Patented July 13, 1915.

Application filed July 23, 1914. Serial No. 852,535.

To all whom it may concern:

Be it known that we, RICHARD BERNHARD and JACOB M. SHOLL, citizens of the United States, residing at Milwaukee, county of 5 Milwaukee, and State of Wisconsin, have invented certain new and useful Improvements in Lubricating Devices for Gyratory Crushers, fully described and represented in the following specification and the accompanying drawings, forming a part of the same.

The object of the present invention is to provide an efficient lubricating system for the eccentrics of gyratory crushers, and particularly for that type of crushers in which 15 the gearing is at the bottom of the eccentric, in which it is not practical to submerge the eccentric in oil, because the gears, also, would be under oil and, on account of their high speed, the lubricant would be churned, 20 heated and destroyed.

The use of oil pumps located outside the crusher is very objectionable as the counter-shaft rotates at high speed, and any driving connection from it must be more or less delicate and liable to get out of order. Gyratory crushers, also, are operated under such 25 conditions of dust and lack of attention that any driving connection from the counter-shaft would not be reliable. Moreover, such 30 crushers are frequently operated in the open air without any housing and during cold weather the oil in pipes outside the crusher will thicken and choke the pump, especially as the oil must be quite viscous in order to 35 carry the high pressure used in such machines. Any type of pump with valves, also, cannot be used, without danger of stoppage of the oil circulation on account of the valves being prevented from seating by dirt, 40 and in cold weather the valves would not operate at all on account of the thickening of the viscous oil.

We avoid the above difficulties, and provide a simple, efficient and durable oiling 45 system, by the use of a valveless pump located within the crusher casing and preferably operated directly by the eccentric, this pump acting to circulate the oil through the eccentric. This oiling system, also, preferably secures the oiling of the gears by the oil 50 circulation, without submerging the gears.

In the accompanying drawings forming a part of this specification, there is shown a gyratory crusher of a well known type embodying all the features in their preferred 55

form, and this construction will now be described in detail, and the features forming the invention then specifically pointed out in the claims.

In the drawings, Figure 1 is a vertical 60 central section of the crusher. Fig. 2 is a horizontal section on the line 2 of Fig. 1. Fig. 3 is a vertical section on the line 3 of Fig. 2. Fig. 4 is a horizontal section taken below the pump cover and showing the gear pump in plan. Fig. 5 is a vertical section 65 on the line 5 of Fig. 2. Fig. 6 is a horizontal section on the line 6 of Fig. 1.

Referring to said drawings, the crusher to which the invention is shown as applied is 70 substantially the same as shown and fully described in United States Letters Patent No. 960,232, dated May 31st, 1910, A being the casing or shell carrying the spider B and closed at the bottom below the eccentric by 75 the cap C. The crushing shaft D carrying crushing head E is suspended in spider B and operated by the eccentric F driven by gears G, H, the latter on counter-shaft I. It will be understood that this particular 80 crusher is shown only for purpose of illustration, and that the invention may be applied to gyratory crushers of other types.

Referring to the parts especially embodying the invention, the eccentric F is provided at its lower end with hollow extension 10, which carries the oil pump. This pump consists of the two pinions 11, 12, having their vertical shafts 13, 14 mounted in block 15, secured in the eccentric extension 10, being shown as secured by bolts 8 passing up through the block 15 into lugs extending inward from extension 10. The shaft 14 and gear 12, are concentric with the eccentric and this shaft is provided with 90 an arm 16, which engages a fixed stop 17 below the pump, so that this arm holds the gear 12 from rotating during the rotation of the eccentric, while the gear 11 is rotated by engagement with stationary gear 12 as 95 the gear 11 is carried about gear 12 by the eccentric. The gears 11, 12 are in an oil chamber 18, having bottom and top walls 19, 20, provided with openings 1, 2, below and above the gears, the opening 1 admitting oil from oil chamber 21 below the eccentric and on one side of the gears, and opening 2 discharging oil from the other side of the gears to space 22 above the pump within the hollow extension of the 110

eccentric below the shaft D. As these gyratory crushers may be operated in either direction, duplicate openings 1, 2, are preferably provided, as shown in Fig. 5, so that 5 either pair of openings can be used according to the direction of rotation of the eccentric, the pair of openings not in use being closed by plugs 3. The oil forced upward by the pump into space 22, flows upward through passages 4 between the shaft D and the inner side of the eccentric, so as to oil this inner bearing, and to the top of the eccentric from which it flows down through passages 5 between the outer side 10 of the eccentric and the eccentric hub, so as to oil the outer bearing of the eccentric, and returning to the hollow space within cap C and to chamber 21 below the pump by passages 6. The pump capacity is larger 15 than that of passages 5, so that the oil collects on the top of the eccentric and overflows through passages 7 to the gear chamber so as to oil the gears G, H, while at the same time not submerging the gears, the 20 level of the oil preferably being just below the gears. A settling chamber for sediment, which readily may be cleaned, is preferably provided by the removable cover 23 closing the oil chamber 21 below the pump. Wear- 25 ing ring 9 for the lower end of extension 30 10 is preferably used and provided with oil grooves for lubrication.

It will be understood that the invention is not to be limited to the exact form or arrangement of parts shown, but that many modifications may be made in the construction and arrangement of the pump and oil passages without departing from the invention.

40 What we claim is:

1. In a gyratory crusher, the combination with the eccentric, of lubricating devices for the eccentric including a lubricant pump located within the casing and operated by the eccentric.
2. In a gyratory crusher, the combination with the eccentric, of lubricating devices for the eccentric including a lubricant pump located below and operated by the eccentric, and passages by which the lubricant is forced by the pump to the top of the eccentric and the outer and inner bearings of the eccentric lubricated.
3. In a gyratory crusher, the combination with the eccentric, of lubricating devices for the eccentric including a lubricant pump located below and operated by the eccentric, passages by which the lubricant is forced by the pump through one bearing of

the eccentric to the top of the eccentric, 60 and passages through which the lubricant returns through the other bearing of the eccentric.

4. In a gyratory crusher, the combination with the eccentric, of lubricating devices for the eccentric including a lubricant pump located below and operated by the eccentric, oil passages by which the lubricant is forced by the pump through the inner bearing to the top of the eccentric, passages 65 through which the oil returns through the outer bearing of the eccentric, and passages through which the oil flows from the top of the eccentric to the gear chamber for lubricating the gears.

5. In a gyratory crusher, the combination with the eccentric having a hollow extension below the shaft, of a rotary lubricant pump within said extension operated by the eccentric, and passages through which the 70 lubricant is fed by the pump to the top of the eccentric for lubricating the eccentric bearing.

6. In a gyratory crusher, the combination with the eccentric, of a valveless submerged 85 rotary lubricant pump located below and operated by the eccentric, and passages through which the lubricant is fed by the pump to the top of the eccentric for lubricating the eccentric bearings.

7. In a gyratory crusher, the combination with the eccentric, of a valveless submerged 90 rotary lubricant pump located below and operated by the eccentric, reversible inlet and outlet passages for operating the pump 95 by rotation of the eccentric in either direction, and passages through which the lubricant is fed by the pump to the top of the eccentric for lubricating the eccentric bearings.

8. The combination with eccentric E, of a gear pump formed by gears 11, 12 carried by the lower end of the eccentric, one of said gears being concentric with the eccentric and held stationary and the other rotating thereon, a lubricant chamber for said pump, and passages through which the lubricant is circulated for lubricating the eccentric bearings.

In testimony whereof, we have hereunto 110 set our hands, in the presence of two subscribing witnesses.

RICHARD BERNHARD.
JACOB M. SHOLL.
